W. H. FRIEDRICH

BANK PROTECTION STRUCTURE

Filed May 1 1922

Attorneys.

UNITED STATES PATENT OFFICE.

WILLIAM H. FRIEDRICH, OF DYER, INDIANA.

BANK-PROTECTION STRUCTURE.

Application filed May 1, 1922. Serial No. 557,783.

To all whom it may concern:

Be it known that I, WILLIAM H. FRIEDRICH, a citizen of the United States, residing at Dyer, in the county of Lake and State 5 of Indiana, have invented new and useful Improvements in Bank-Protection Structures, of which the following is a specification.

This invention relates to building structures, and more particularly a structure of the bank protective type. The structure has been designed for small banks to protect the same from "hold-ups," and it consists in a novel combination and arrangement of 15 parts to be hereinafter described and claimed.

In order that the invention may be better understood, reference is had to the accompanying drawing, in which:

Figure 1 is a sectional view of a fragment of the building, and Fig. 2 is a section on the line 2—2 of Fig. 1.

Referring specifically to the drawing 5 denotes a room on the ground floor of a 25 building. This room is occupied by a banking establishment and it contains the usual fixtures of such an establishment. As shown in the drawing, the room contains a cage or compartment 7 for the teller and 30 other officers of the bank, together with a counter 8 for the patrons. Inside the compartment 7 is a counter 9 for the teller and other bank officials.

Directly above the banking room 5, and 35 isolated therefrom, is a vault room 10 in which the money and other valuables are kept. For the purpose of transferring the money, etc., from the room 10 to the room 5 during the business hours of the bank, and 40 for transferring the same back to the room 10, a small elevator 11 similar to a dumb-waiter has been provided, the same traveling in a shaft 12 extending between the two rooms. The elevator shaft 12 terminates at 45 the bottom at the teller's counter 9 so that the teller may have access to the elevator 11 without leaving his station.

By the structure hereinbefore described, it is not necessary to keep a supply of 50 money on the teller's counter 9, the money, as needed, being supplied from the room 10 above by means of the elevator 11. It will be understood, that the teller will communicate to the attendant in the room 10 55 above the amount of money required, and this attendant then places the money in the

elevator 11 and lowers the same to the teller's counter 9.

In the floor of the room 10 are set lights 13 so that the occupant of said room may 60 observe what happens in the room 5 below, and take proper action in the event of an attempted robbery. In the floor are also set swiveled blocks 14 having vertical holes or ports 15 through which may be inserted 65 the barrel of a gun or other fire-arm for firing at robbers in the room 5. For the protection of the occupant of 10, the lights 13 may be of bullet proof glass.

A one-man elevator 16 also establishes 70 communication between the rooms 5 and 10. The door opening from the elevator shaft 17 into the room 10 is shown at 18. The door opening from the elevator shaft into the room 5 will be kept locked to prevent 75 unauthorized persons going from said room to the room 10 above. The door 18 can also be kept locked and under the control of the occupant of the room 10, so that he may refuse to open the same if a demand is 80 made by an unauthorized person.

Communication between the rooms 5 and 10 may also be had by providing the enclosed stairway shown dotted at 19 in Fig. 2, the same having top and bottom doors 85 arranged in the same manner as the elevator doors. With elevators of the type suggested as a standard product and easily installed, it will be understood that preference will 90 be given to them over stairways, due to the saving of space and time occasioned.

The advantages of the novel arrangement above described should be readily apparent. First, the bulk of money in bills and coin is 95 concealed from the view of those approaching the cage 7, so that an immediate object is not presented to foster covetousness in unprincipled minds. Further, in the event of an attempted robbery, failure to find the bulk of funds on the bank floor will relieve 100 the officers or clerks in charge of responsibility, as well as of threats of physical attack or violence usually resorted to in such instances. The hazard of bodily injury or 105 loss of life will be greatly minimized as the intruders realize the helplessness of the officers and clerks to produce the bank's funds. While the intruders are in action, they will of course be under the observation of the occupant of the vault room above, and in 110 danger of being attacked by gun fire. In any event, the funds of the bank are main-

tained in a remote and ordinarily inaccessible place, which in lending safety to the same, should make for a substantial reduction in insurance rates.

With the advantages of the system enumerated in a positive sense, it is proper to add an advantage in the negative sense. Thus, the presence of the arrangement in a bank may of itself discourage or prevent an attempt at robbery. It being evident that surprise or "hold-up" robberies of banks are usually prearranged and well calculated, it is probable that a study of the operation and layout of the bank would be made in advance; and, the plotters finding that the bank funds are not readily available, and that the danger of capture or bodily injury is greatly increased, the plan would in all probabilities not be put into action, making the institution more or less immune to robbery.

While the vault room has been shown with a window facing the street, it should be understood that where such a frontage amounts to an exposure, suitable measures will be taken to provide such means to protect the room as will make for the highest degree of safety.

In summarizing, it will be seen that the upper room 10 extends over the customer's compartment 5 as well as the attendant's compartment behind the partition 7. There-

fore, an attendant in the upper room 10 is not only able to co-operate with the attendant below in handling money, but is also able to make observations by way of the sight opening 13 and to insert a gun through the ports 15 in an emergency. By providing means whereby one attendant in the upper room 10 may conveniently perform these three duties the cost of service and protection of the bank's funds and employees is maintained comparatively low.

I claim:

In a banking house, the combination with a lower room having a partition defining customer's and attendants' compartments, of an upper room arranged directly over the customer's and attendants' compartments and having a floor, a money conveying elevator movable between the attendants' compartment and said room, a shaft receiving the elevator, the floor of the upper room being provided directly above said customer's compartment with observation means and with openings for the passage of guns whereby a single attendant in the upper room may co-operate with the attendant in the attendant's compartment and may also observe and cover with firearms those in the customer's compartment below.

In testimony whereof I affix my signature.

WILLIAM H. FRIEDRICH.
